(57) **CLAIM**

The ornamental design for footwear tread pattern including star shaped treads, as shown and described.

DESCRIPTION

FIG. 1 is a bottom plan view of a footwear tread pattern including star shaped treads showing my new design;

FIG. 2 is a front elevational view thereof;

FIG. 3 is a rear elevational view thereof; and,

FIG. 4 is a side elevational view thereof.

The broken dot-dash line(s) define the bounds of the claim and form no part thereof.

The dash-dash broken lines shown in the drawings represent unclaimed environment and are for illustrative purposes only, forming no part of the claimed design.
